UNITED STATES PATENT OFFICE.

HARRY F. SMITH, OF CINCINNATI, OHIO.

DESIGN FOR A BADGE OR SIMILAR ARTICLE.

SPECIFICATION forming part of Design No. 30,387, dated March 28, 1899.

Application filed February 2, 1899. Serial No. 704,296. Term of patent 7 years.

To all whom it may concern:

Be it known that I, HARRY F. SMITH, a citizen of the United States, residing at Cincinnati, in the county of Hamilton and State of Ohio, have invented and produced a new and original Design for a Badge or Similar Article; and I do declare the following to be a full, clear, and exact description of the same, reference being had to the accompanying drawings, forming a part thereof.

As shown in the drawings, the leading or material feature of my design consists in a circular part or button 1, surmounted by the head 2 of an elk, shown in profile and having antlers 3 bent in the same plane with the button 1 to represent as nearly as possible the natural curvature or projection of an elk's antlers. The circular part of the button 1 has produced upon its face, as shown at 4 in

Fig. 1, the representation of a watch-dial, numbered from "1" to "12" and having hands 5 pointing to the hour of eleven o'clock. The button 1 has a back 6 upon its stem or shank 7, and, as shown in the drawings, said back is of substantially the same diameter as the button itself.

It is apparent that this design is also applicable to badges, charms, lockets, and other similar articles.

Having thus described my invention, what I claim, and desire to secure by Letters Patent, is—

The design for a badge, or similar article, substantially as herein shown and described.

In testimony whereof I affix my signature in presence of two witnesses.

HARRY F. SMITH.
